UNITED STATES PATENT OFFICE

ROLAND CHILTON, OF KEYPORT, NEW JERSEY, ASSIGNOR, BY MESNE ASSIGNMENTS, TO AEROMARINE PLANE & MOTOR COMPANY, INC., OF KEYPORT, NEW JERSEY, A CORPORATION OF NEW YORK

AIRPLANE CONTROL

Application filed April 18, 1929. Serial No. 356,128.

This invention relates to airplane controls, and in a specific aspect to lateral or aileron control means. A prime object of the invention is to provide a new organization of control mechanism and movable control surfaces which shall maintain effective control at and beyond the "stall".

As is well known in the art, the lift of an airfoil increases with an increase of the angle of attack up to a critical angle identified with the "burble" point whereat the streamline flow over the wing breaks down and a sudden loss of lift occurs causing an actual drop of the airfoil in flight; and unless this resulting drop is, fortuitously equal on the right and left hand wings, the well known "spin", which is regarded as the most prevalent danger in flying, results. This auto-rotation follows from the facts that; beyond the stall, the wing having the greater angle of attack has the least lift and that the faster falling wing has in effect a greater angle of attack than the other. The faster falling wing having the least lift obviously results in a tendency towards increased rotation.

It must be kept in mind that the angle of attack is the angle between the wing chord and the actual line of travel of the airplane, which last, at the stall, will be steeply downwards although the nose of the machine is steeply above the horizon.

Conventional ailerons comprise hinged flaps at the trailing edge of the wings connected for opposite displacement by lateral movement of the control "stick"; the mean angle of the right and left hand ailerons being always that of the wing, wherefrom it results that when the wing is stalled the aileron also loses effective lift (negative lift in the case of the upturned aileron) and such lateral control means are accordingly ineffective at or after the stall. Thus lateral control is lost and the pilot is unable to correct an incidental excess drop in one wing which initiates the turning which develops into auto-rotation by the resulting difference in lift between the faster and slower dropping wings. The only remedy in present machines is to first cure the stall by nosing down the ship to regain flying speed in order to

bring the angle between the wing and the steep path of descent in spin to less than the stall angle, whereupon the wing with the greatest effective incidence will have (as is normal) the greatest lift and the auto-rotative tendency ceases and the ailerons resume their functions.

For longitudinal stability planes are balanced so that the tail surface has "negative load", i. e. the air reactions thereon are downward so that a stall results in a loss of positive lift in the wings and of negative lift in the tail whereby the nose goes down and the tail up; the resulting dive restoring flying speed automatically if auto-rotation has not intervened and set up a gyroscopic couple which keeps the nose up. This dive and recovery, however, absorbs a few hundred feet of altitude and hence the crashes that follow stalls at low altitude. These dangers may be avoided by so arranging the ailerons that they remain uninstalled after the wings have reached the burble point, and a prime object of the invention is to provide simple and effective means whereby this may be realized in practice.

It has been proposed to dispose the ailerons away from the trailing edge of the wing so that they may work in air undisturbed by the stalled wing, but this alone does not prevent the ailerons themselves from stalling with the wings because both participate in the pitching movement of the whole ship (with conventional controls) so that both (the ailerons and the wing) have the same mean angle of incidence, any difference in angle between the separate ailerons merely resulting in the one at the greater angle of incidence being worse stalled.

The present invention on the contrary provides a novel and simple control system wherein the ailerons do not follow the pitching movement of the airplane but are floated to always align their mean angle to the direction of movement of the ship thru the air, only the angle between the ailerons being determined by the pilot's control, in opposition to the conventional arrangement wherein the mean angle of the two ailerons is fixed at or near parallelism with the wing chord.

The ailerons in the present invention accordingly are floated pivotally ahead of their center of pressure so as to possess "weather-vane" stability whereby they are free in flight 5 to align their mean angle to the flight path even tho this path be at a great angle to the wing chord (as in a stall); and the angle between the ailerons only is controlled.

The mechanism is so arranged that the automatic unitary movement of the two ailerons 10 relative to the airplane as a whole (which may occur without change in the angle between the ailerons) results in a vertical movement 15 of the control "stick" grip whereby the pilot may "feel" the altitude of the ailerons, which will give him an index of the actual angle of attack of his ship and warn him should he be approaching the stall angle. When he wishes to do this as in landing, the differential 20 movement between the unstalled ailerons (by lateral movement of the stick as usual) will enable him to maintain lateral control when (with the normal ailerons) they are rigid with the ship as to their mean angle 25 the lateral balance of the ship being dependent merely on its inherent stability and the absence of unequal air gusts at the wings.

Such maintenance of lateral control after the stall will have an important advantage 30 additional to the avoidance and correction of spins as follows:

It is well known that the slowest landing (and, therefore, the most desirable as regards 35 constricted or rough landing areas) is that made at a complete stall whereat the actual path of travel of the airplane is much steeper than in the normal glide, even tho the nose of the ship be held relatively high, a condition described by pilots as "squashing". Except 40 in ships of exceptional inherent lateral stability and in steady air conditions, this "squashing" cannot safely be initiated except very close to the ground because of the danger of one wing dropping resulting in "slipping in" which, from a substantial height, involves a crash landing on one wing. However, the relatively steep path of descent while "squashing" is of great advantage in 45 clearing an obstacle for landing in a restricted area beyond, and is a method successfully used for obtaining slow and short landings by pilots having sufficient assurance that they can maintain the ship accurately in the very narrow range of altitude between "squashing" and stalling. The ordinary pilot with 50 the present aileron controls is usually well advised in avoiding this method. It is one object of the present invention to enable a ship to be flown indefinitely at the stall with safety in the hands of a relatively inexperienced pilot so that he may be able to make a short and slow approach in order to successfully negotiate an emergency landing in 55 a tight field.

60 The foregoing advantages of floating aile-

rons differentially controlled are conceded by many of those skilled in the art (of theoretical aerodynamics) but great mechanical difficulty and complication in such control systems as have been previously proposed is usually alleged as the reason that these advantages have not been reduced to practice. 70

The prime object of the present invention is to provide a simple and direct control system, readily applicable to conventional airplanes, which will permit the desired automatic alignment of the mean angle of the two ailerons with the actual flight path, whilst maintaining effective control of the angle between the ailerons. A further object consists in introducing an additional movement to the control "stick" (in this instance a vertical movement) proportional to the mean angle of the two ailerons to the wing chord, whereby the pilot may "feel" 80 the automatic changes in this angle which will be an index of the actual instantaneous angle of attack and whereby he may further, by opposing or assisting such movement, be provided with an additional control 85 movement effective longitudinally (or in pitch). A still further object is to achieve the foregoing without changing the normal control movements from those which have become the standard familiar to all pilots. 90

For convenience of explanation the word "stick" has been used to designate the control member manipulated by the pilot but it will be obvious that the provisions of this invention are equally applicable to a wheel 100 or other type of control member.

Various other objects and advantages of the invention will be in part obvious from an inspection of the accompanying drawings and a careful consideration of the following particular description and claims of one form of mechanism embodying my invention. 105

In the drawings:

Fig. 1 is a perspective diagrammatic view of an airplane equipped with the aileron control of this invention. 110

Fig. 2 is a perspective view on a larger scale showing the control mechanism.

Referring to Fig. 1 a low wing monoplane having wing tip type ailerons 10 and 11 is indicated, but it will be understood that the invention is applicable to any type of wing arrangement. The wings 12 and 13 are equipped with aileron shafts 14 and 15 extending from the ends of the wings and about which the ailerons 10 and 11 are arranged to pivot. Near the center line of the ship, as shown in enlarged view in Fig. 2, are a pair of rocking shafts 16 and 17 and these are respectively connected by any suitable means so as to partake of the motion of and transmit motion to the ailerons. The connecting means illustrated comprise rocking levers 18 and 19 secured to the ends of the shafts 16 and 17 and corresponding levers 20 and 21 125 130

secured to the ailerons; the levers being connected by cables 22 and 23 brought over suitable pulleys 24 and 25. Secured to the rocking shafts 16 and 17 are approximately horizontal levers 26 and 27 and a conventional control "stick" 30 is mounted for rocking motion with a longitudinal shaft 31, the connection being pivotal for fore and aft of the stick which is transmitted to the longitudinal control surfaces 32 of the tail by any suitable means such as the rod 33 and the levers 34 and cables 35. Slidable upon the stick 30 is an outer tube 36 having a grip 37 and equipped at its lower end with a rigid cross head 38 terminating in the eyes 40 and 41 on respective sides above the extended ends of the levers 26 and 27. These are engaged by the links 42 and 43 so that the effect of locking the control stick laterally is to raise one lever and depress the other. The ailerons partake of this motion by means of the cable connections previously described.

It will be seen that on account of the vertical freedom of the outer tube 36 with the grip 37, the control levers 26 and 27 are free to rise and fall vertical in a unitary manner and that such unitary motion (without change in angle between the levers or the connected ailerons) is free to occur when the stick is maintained vertical in which condition no change of relative angle between the ailerons is possible. At the same time when the stick is held over to one side a corresponding difference in the angle between the ailerons is enforced without, however, enforcing any specific mean angle of the ailerons relative to the ship as a whole. Thus the ailerons at all times are free to align themselves with the actual flight path of the ship whereby they will remain unstalled, even though the wing be brought past the stalled position. To insure the automatic alignment of the ailerons with the air stream, the aileron mounting shafts 14 and 15 are disposed ahead of the center of pressure of the aileron surface whereby the aileron possesses weather-vane stability.

It will be seen that as the ailerons together change their angle, (from change in the relative direction of the air stream over the wing) they will impart a vertical movement to the floating outer tube of the "stick" which will be felt by the pilot and may, in fact, be in a certain degree initiated or resisted by him which will give him a longitudinal control auxiliary to the normal control afforded by the horizontal movable tail surfaces, which latter will be responsive to fore and aft movement of the stick in the usual way.

The ends 40 and 41 of the cross lever 38 which is rigid with the floating tube 36 are preferably disposed at about the same horizontal level as the shaft 31 which forms the rocking axis of the "stick" so that little or

no side motion of the tops of the links 42 and 43 occur.

It will be seen that with a relatively slight mechanical addition to the conventional control arrangement differential control for floating ailerons is provided.

Variations may be resorted to within the scope of the invention and portions of the improvements may be used without the others, whilst not departing from the spirit of the invention.

Having thus described my invention, I claim:

1. The combination with an airplane wing including, a co-operating pair of pivotally mounted ailerons having weather-vane stability tending to enforce alignment of the ailerons with the flight path independently of the attitude of the wing, and control means adapted to define the angle between the two ailerons and floating as to the mean angle of the two ailerons relative to the wing, said control means including a rockable control member, a tube slidable on said member and having a hand grip, and a two-arm cross head rigid with said tube and operatively connected to the respective ailerons.

2. In an airplane in combination, a pair of pivotally mounted ailerons connected so as to be together free for self-alignment with the flight path of the airplane, and control means having free vertical movement affording said freedom and adapted to control the relative angle of the two ailerons responsive to lateral movement of the control means.

3. In an airplane in combination, a pair of ailerons, a control member connected thereto to enforce opposite angular movement of the ailerons when the control member is rocked, said control member being floated vertically to permit free unitary movement of the two ailerons.

4. The combination with an airplane, of a pair of ailerons freely pivotally mounted for automatic unitary angular movement responsive to changes in attitude of the airplane, and control means floated vertically to afford said freedom and adapted when moved laterally to move the ailerons simultaneously and in opposite directions.

5. In an airplane control system, the combination of, a pair of floatingly pivoted ailerons, a rockable control means having unrestrained vertical movement and adapted when held against rocking to restrict the ailerons to unitary movement and when rocked to move the ailerons in opposite directions.

6. A control system for actuating airplane ailerons from a rockable control member including in combination, levers connected to respective ailerons, a cross-head rigid angularly with the control member and freely slidably mounted thereon, a hand grip slidable with said cross-head, and connecting

means between the ends of said cross-head and the respective levers.

7. In an airplane having a control stick rockably mounted on a horizontal shaft, in combination, a pair of ailerons pivotally mounted, levers pivotally mounted on each side of said shaft and connected so as to control respective ailerons, a cross-head mounted for rocking motion with said stick and at all times freely slideable thereon and connected to control the angular relation of said levers.

8. In an airplane having a pivotally mounted control member in combination, aileron control means on each side of said pivot, a cross-head angularly rigid with the control member and at all times freely slideable thereon, a hand grip rigid with said cross-head, and means adapted to connect each end of said cross-head to the respective aileron control means.

9. In a system for actuating the control surfaces such as ailerons in an airplane, the combination of a pair of control surfaces, a control stick mounted for rocking movement, an operating member mounted for automatic sliding longitudinally thereon and provided with rigid laterally extending arms, a pair of lay shafts disposed one on either side of said control stick and having levers connected with the above said arms for movement of the shafts thereby respectively, said control surfaces being operatively connected to said shafts.

Signed at Keyport, in the county of Monmouth, and State of New Jersey this 15th day of April, 1929.

ROLAND CHILTON.
